UNITED STATES PATENT OFFICE.

LEO STEIN, OF ROCHESTER, NEW YORK, ASSIGNOR TO THE STEIN MANUFACTURING COMPANY, OF SAME PLACE.

DESIGN FOR A BURIAL-CASKET LID.

SPECIFICATION forming part of Design No. 19,724, dated March 25, 1890.

Application filed December 11, 1889. Serial No. 333,362. Term of patent 14 years.

To all whom it may concern:

Be it known that I, LEO STEIN, a citizen of the United States, residing at Rochester, in the county of Monroe and State of New York, have invented and produced a new and original Design for Burial-Casket Lids, of which the following is a specification, reference being had to the accompanying drawings, forming a part thereof.

- 10 Figure 1 is a plan view of the burial-casket lid, showing my design; and Fig. 2 is a sectional view taken on line $x-x$, Fig. 1, further illustrating the design, which, it is thought, is sufficiently illustrated by these two views.
- 15 The leading feature of my design consists in a bordering molding for the lid, a panel depressed below the plane of said bordering molding and disposed in substantially a horizontal plane, and a cross-bar for dividing the
- 20 lid into head and foot sections, and disposed with its top face in line with the top plane of said bordering molding.

25 The panel a of my burial-casket lid is disposed in substantially a horizontal plane, and contiguous with the said panel and raised above its plane is a bordering molding b , which produces a very pleasing, novel, and desirable form. Arranged between the extremities of the panel a is a cross-bar c , which

divides the same into head and foot sections, 30 and is raised above the plane of the panel a and into the same plane as said molding, thus breaking the sameness of effect produced by the continuous panel and greatly adding to the general appearance and effect of the 35 casket-lid.

Having thus fully described my invention, what I claim as new, and desire to secure by Letters Patent, is—

40 The design for burial-casket lids herein shown and described, the same consisting of a flat surface or panel disposed in substantially a horizontal plane, a bordering molding raised above the plane of said flat surface or panel and contiguous therewith, and a 45 cross-bar dividing the lid into head and foot sections and disposed with its top face in the same plane as the top of said bordering molding, substantially as set forth.

50 In testimony whereof I have hereunto signed my name, in the presence of two attesting witnesses, at Rochester, in the county of Monroe, in the State of New York, this 6th day of December, 1889.

LEO STEIN.
